LAMP EJECTOR

George B. Kurtzon, Chicago, Ill., assignor to Garden City Plating & Mfg. Co., Inc., a corporation of Illinois

Application February 25, 1939, Serial No. 258,434

1 Claim. (Cl. 173—328)

This invention relates to a lamp fixture adapted to accommodate a double-ended elongated type of lamp and particularly to a manually operable means for ejecting the lamp from the sockets thereof.

The lamp fixture in accordance with the present invention may comprise an elongated light-reflecting housing and a pair of opposed sockets which are adapted to receive an elongated tubular incandescent lamp or a lamp of the fluorescent type. One such lamp fixture is described in an application of Carl Krauss, Serial No. 246,050, filed December 16, 1938. In accordance with that application, the sockets are designed to receive and have removed therefrom the contact pins or prongs at both ends of the lamp in a plane substantially at right angles to a line drawn through the axes of the contact pins, thereby enabling the lamps to be inserted or removed therefrom by a transverse movement.

Lamp fixtures of this general character are especially designed for use in glass show-cases for merchandise display purposes. Since, for esthetic purposes, these lamp fixtures are designed to provide a minimum of excess width of the housing over that of the lamp, considerable difficulty is entailed in the efforts to remove the lamps from the sockets. The reason being that there is generally insufficient clearance space between the lamp and the housing to enable the fingers of an individual to encircle and firmly grasp the lamp.

The present invention is an improvement over that described in the application of Carl Krauss referred to above as well as over other lamp fixtures designed for use in connection with the elongated type of lamp, in that manually operated means are provided to eject the lamp from the sockets and thereby enable the facile withdrawal or removal of the lamp from the lamp fixture.

The lamp fixture including the novel lamp ejecting means embodying my invention is simple in design and construction and inexpensive to manufacture. Moreover, the lamp ejecting means are readily and easily operated to eject the lamp from the sockets.

The present invention has many other advantages which will be made apparent in the description of two preferred embodiments, however, my invention is not to be construed as limited to the details of the invention described and shown in the drawing except as included within the scope 55 of the appended claim.

In the accompanying drawing, which illustrates the invention:

Figure 1 is a horizontal sectional view taken on the line 1—1 of Fig. 3, through a lamp fixture in accordance with my invention with parts broken away, showing the lamp, sockets and lamp ejecting means in elevation with the lamp ejecting means in inoperative position;

Fig. 2 is a fragmentary horizontal sectional view similar to Fig. 1, showing the lamp in elevation and ejected from the socket with the lamp ejecting means in operative position;

Fig. 3 is a transverse sectional view on the line 3—3 of Fig. 1 showing the construction of the sockets;

Fig. 4 is a fragmentary horizontal sectional view, similar to Fig. 1 of a modified form of lamp ejecting means, the lamp ejecting means being in inoperative position;

Fig. 5 is a fragmentary horizontal sectional view, similar to Fig. 2, showing the lamp ejecting means of Fig. 4 in operative position; and

Fig. 6 is a perspective view of the socket mounting shown in Figs. 4 and 5.

Referring particularly to Figs. 1-3, there is shown a narrow elongated lamp housing 10, preferably of metal, bent to form a generally C-shaped section, which is especially adapted for use in a glass show case. The free longitudinal edges of the housing are inturned at 11, Fig. 3, forming pockets. A metallic reflector 12 has its longitudinal edges sprung into the pockets, causing it to assume a curvilinear form within the housing. The ends of the housing are closed by walls 13 and 14.

Within the housing 10 and spaced from the walls 13 and 14 are a pair of opposed sockets 15 separated a suitable distance to accommodate a lamp 16. Each socket is mounted within the housing in any desirable manner. As shown, each socket is provided with a removable back cover plate 25, of insulating material, which is secured in any desirable manner, as by a suitable adhesive material, to the downwardly extending leg 16' of an inverted L-shaped bracket 19. The other leg 17 of bracket 19 is provided with lateral downturned edges, one edge 20, being rigidly secured to the housing as by the bolt 18. The other edge 20', being supported in a reverse bend in the housing at 21. In this manner, sockets 15 are securely and, at the same time, removably fastened to bracket 19 and the latter, in turn, to the housing.

Lamp 16 is of elongated tubular shape and is provided at each end with a base 22 into which

is molded a pair of contact pins or prongs 23 and 24. The bases are so adjusted that all of the contact pins lie in the same plane. Lamp 16 may be suitably of the fluorescent type sold in the 5 trade under the trade-mark "Lumiline"; however, other types may be used, if desired.

Each socket 15 comprises a molded base of Bakelite or other suitable insulating material having the general outline of a U and has housed 10 therein a pair of contact members 26 and 27. The contact members may be formed of any suitable conducting material such as a phosphorus-bronze spring alloy or the like. The contact members have one end shaped to provide a pair 15 of spring jaws (Fig. 3) to receive the contact pins 23 and 24 on the lamp. These jaws are normally disposed in suitable openings within the base of each socket, and are so dimensioned with respect to the size of the openings as to 20 permit of the necessary play on insertion or removal of the contact pins. The other ends of the contact members are arranged to provide a means of contact with the binding or terminal screws 28 and 29 which are threaded into the 25 substantially flat top portion of the Bakelite base. These contact members are maintained in position within the base and covered by the back plate 25.

The front face 30 of the Bakelite base of each 30 socket is provided with a pair of spaced parallel recesses 31 and 32 which establish communication between the contact pin receiving spring jaws of the contact members 26 and 27 and the lower or curved edge of the base. It is now obvious that by a simple transverse movement of lamp 16 in a plane substantially at right angles to a line drawn through the axes of contact pins 23 and 24, these pins can be inserted in or removed from the spring jaws of the contact members 40 within the sockets. In Figs. 1 and 3, I show lamp 16 inserted in sockets 15.

To eject the lamp from the socket to the position shown in Fig. 2, I provide a pair of suitable pivoted, lever-type ejectors 33 which can be 45 manually operated to accomplish the desired purpose. Preferably, and as shown in the drawing, each ejector is pivotally secured to a single socket and is used in association therewith; however, this is not essential since the ejectors may be 50 pivotally secured as desired within the housing. Since both ejectors are identical in construction, only one will be described in detail.

Ejector 33 is of generally inverted L-shape and 55 comprises a horizontally extending arm 34 and a downwardly extending lever arm 35. Arm 34 is provided with a semicircular or inverted trough-like portion 36 which extends over and partially surrounds the end of lamp 16 adjacent to the socket. The outer free end of semi-circular portion 36 is upturned as at 37 so as to present a rounded surface which will press against the lamp bulb to eject the latter from the sockets in a manner to be described. The other end of 60 arm 34 is bifurcated to provide a pair of spaced flanges 38 which are disposed on opposite sides of the socket and extend rearwardly thereof. Each flange 38 is provided with an upstanding ear 39 through which a pivot pin 40 extends for pivotally securing arm 34 to the socket. Lever arm 35 extends between flanges 38 and is secured thereto in any desirable manner. As shown, lever arm 35 is formed with laterally disposed flanges 42 which are riveted to flanges 38 as at 41. It 70 will be noted from Fig. 1 that the lever arm is positioned substantially adjacent to and parallel 75

with leg 16' of bracket 19 and extends downwardly to a point beyond the lower or curved edge of the socket.

The operation of the lamp ejecting means is now apparent. When it is desired to remove 5 lamp 16 from the sockets; that is, from the position shown in Fig. 1 to that shown in Fig. 2, lever arms 35 are pushed away from the lamp. This causes arms 34 to pivot downwardly about 10 pivots 40 and bring curved portions 36 into contact with the lamp bulb, ultimately pushing the contact pins 23 and 24 out of the spring contacts 26 and 27. The lamp then occupies the 15 position shown in Fig. 2 and may then be withdrawn or removed readily from the sockets.

In constructing lamp fixtures in accordance 20 with my invention, I prefer to wire the sockets 15 prior to insertion thereof in the lamp housing. These wires, designated by the numeral 45, extend through a bushing 46 in end wall 14 and are attached to the terminal screws 28 and 29 as shown in Fig. 1. The wires (not completely shown) to the socket remote from bushing 46 are carried along behind reflector 12, and all of the 25 wires are retained in position by a supporting plate 47 formed as an angle bracket and secured to the housing by screws 48 near end wall 14.

In the modified form of my invention, Figs. 4 to 6, there is shown a housing 50, reflector 51, 30 lamp 52 and sockets 53, all substantially identical to the corresponding parts 10, 12, 16 and 15, respectively, heretofore described in connection with Figs. 1 to 3. In this form of my invention, however, sockets 53 are tiltably secured to brackets 54 within housing 50 thereby enabling lamp 35 52 to be readily removed therefrom in the manner to be hereinafter described. Since these brackets are identical, only one will be described in detail.

Bracket 54 is bifurcated at one end, as at 55, providing a pair of spaced parallel flanges 56 and 40 57. One lateral edge of flange 57 is downturned, similar to edge 20, and is rigidly secured to housing 50 as by a bolt (not shown) and as described in connection with edge 20. One lateral edge of flange 56 is also downturned, being similar to 45 downturned edge 20', and is secured in a reverse bend in the housing in the manner described in connection with edge 20'. The other end of bracket 54 is imperforate and is provided with a 50 pair of laterally depending opposed ears 59 and 60, by the aid of which socket 53 is tiltably secured to bracket 54.

Socket 53 is provided with a plate 61 secured to the backside thereof. Plate 61 has an extension 62 at the lower end thereof which extends 55 below the bottom of the socket and provides a handle by means of which the socket can be tilted. At the upper end of plate 61, there is provided a pair of parallel, laterally opposed ears 63 and 64 which cooperate with ears 59 and 60 60 and a pin 65 passing through them to provide the tiltable mounting for the socket.

In the operation of this form of invention, lamp 52 may be readily removed from housing 50 by pushing outwardly on extensions 62 there- 65 by tilting sockets 53 to the position shown in Fig. 5, out of engagement with the contact pins 66 of the lamp. The movement of the sockets back to the normal position of Fig. 4 in which position the lamp may be inserted in the sockets, is readily accomplished in an obvious manner. Suitable stop means (not shown) may be provided to arrest return movement beyond the normal position.

While I have described my invention in con- 75

nection with a preferred form of socket, it is obvious that my invention may also be used in connection with other sockets of a similar type, designed for use with the elongated type lamp, 5 to eject the lamp therefrom. It is also obvious that only one lamp ejecting means may be used since substantially the same results are obtained as in the case with the two lamp ejecting means shown and described.

10 I claim:

An ejecting type of socket for a lamp having pin type terminals, said socket comprising an insulating base having a flat face against which the lamp base is adapted to be disposed, said face 15 having a plurality of straight parallel slots extending from the face edge to inner points on said face and being deep enough to accommodate con-

tact pins projecting from said lamp base, spring contacts in said slots at said inner points for cooperation with said pins to make and break connections when said pins are moved along said slots to and from said inner points respectively, 5 and an ejecting member pivotally mounted on said socket base, said member consisting of a hood portion normally extending over a portion of the lamp and wing portions embracing opposite sides of said base, each of said wings having a pivot pin extending therethrough and into the side of said base, said wings and hood being so disposed that the hood may be moved generally across the flat face of the base in a direction to eject a lamp. 10 15

GEORGE B. KURTZON.
